(57) **CLAIM**

The ornamental design for a vehicle escape device, as shown and described.

DESCRIPTION

2. Vehicle escape device

2.1 : Perspective

2.2 : Front

2.3 : Back

2.4 : Right

2.5 : Left

2.6 : Top

No. 2: Figs. 2.1-2.6 display a vehicle escape device, comprising a hammer with a spring-loaded hammer impact point at its top end and a seatbelt cutter at its side; dashed lines represent optional features of the design, which do not limit the scope for which protection is sought.
